TRANSMISSION SYSTEM

Hugo Cohn, New York, N. Y., assignor to Radio Receptor Co. Inc., New York, N. Y., a corporation of New York

Application January 16, 1934, Serial No. 706,901

10 Claims. (Cl. 179—2)

The invention relates to a system by which periodic signals may be transmitted to various points and also various programs of music, speeches, radio broadcasts and the like may also be transmitted to the same various points. The system is so arranged that its use for one type of transmission will not preclude its use for the other type of transmission.

Without intending to limit the invention, but for the purpose of clearly disclosing it in a simple manner it may be described as applied to a school system. It will be understood, of course, that the invention is not limited to school systems but may be employed in whole or in part in other connections such as hospitals, hotels, auditoriums and other installations.

In many schools there is installed a clock associated with mechanism for causing signals such as bells or the like in various rooms of the school to be sounded at appropriate predetermined times. It is a purpose of the present invention to associate with such a system a loud speaker at each of the school rooms where the time signal is sounded or at certain selected ones. There may be associated with the system a receiver which may be a microphone or a radio receiver or a phonograph or the like to bring to the system certain sounds which are to be delivered through the loud speakers. The apparatus in each room may be controlled by a switch which may allow the bell-ringing or signal current to go to it, or which may allow the current from the receiver, which may be referred to as the talking current, to go to it. There also may be associated with the system mechanism or switches by which the talking current may be led to the apparatus in all the rooms or in a group or groups of rooms. There may also be provided mechanism or a switch preferably automatic in its operation controlled by the program clock for closing the signal circuit for a short time to sound the signals in proper rooms at the times for which the program clock may be set even when the talking circuit is in operation. This mechanism preferably will be such as not to permanently interrupt the talking circuit but to allow it to continue to operate after the signal required by the clock has been given.

In the accompanying drawings Figure 1 is a diagrammatic showing of one form of system involving the invention in which the bells or other signalling devices in the individual rooms are operated by direct current or by alternating current. Fig. 2 is a similar diagrammatic view of a

system in which the bells or signalling devices may be operated by alternating current.

In Figure 1 a source of direct current 10 is indicated for operating the various signaling devices, illustrated as bells. This may consist of a battery or any other suitable source. A2 designates generally the apparatus in one room consisting of a signaling device 11 which may be a bell or other suitable mechanism. In parallel with this in the room A2 is shown a loud speaker 10 12. Similarly A3 indicates a room in which is a signaling device 13 in parallel with a loud speaker 14. B2 indicates a room in which is a signaling device 15 in parallel with a loud speaker 16 and B3 indicates a room in which is a signaling device 17 in parallel with the loud speaker 18. It will be understood that the signaling devices do not operate with the alternating current which operates the loud speakers and the loud speakers do not operate normally with the direct current 20 which operates the signaling devices. This is effected by suitable selection and installation as is well known in the art. If the signaling system is direct current the loud speaker may click when the current is made and when the current is 25 broken, and in some circumstances may even buzz slightly; if the signaling system is alternating current, the loud speaker may buzz more or less loudly depending upon the frequency but this is negligible and does not impair the usefulness of 30 the system.

PC indicates a program clock which together with the other apparatus about to be described may be located at any suitable point in the school. It may be convenient to place this at some central point such as the office of the principal or convenient thereto. As is usual, the program clock is indicated as having a number of ringing circuits marked 1, 2, 3, 4, 5 and 6 so that different bells or different groups of bells may be operated on 40 different schedules and there is provided an interconnecting board indicated generally by the letter B provided with a plurality of busbars corresponding to the six circuits of the program clock PC. These are so arranged that one or a plurality or all of the signaling devices in the various rooms may be connected to any one of the busbars by plugs, screws, or other means, in the manner well known in the art. In Fig. 1 the plug A2P is indicated in place as connecting the apparatus of 50 the room A2 with the busbar associated with station 2 on the program clock PC. The plug B2P connects the apparatus in the room B2 with the busbar associated with the station 2 on the program clock PC. Likewise the apparatus in the 55

rooms A3 and B3 is connected to the busbar associated with station 3 of the program clock PC by means of the plugs A3P and B3P respectively. Apparatus in other rooms (not shown) may be connected to these or other busbars in ways well known in the art. The dotted lines on the program clock PC indicate connections with the busbars through the program clock to one side of the battery 10. It will be understood of course that these connections are normally open but are closed by the program clock at predetermined times.

Arranged at a suitable place which may be centrally located adjacent the program clock PC and away from the rooms are a plurality of controlling switches one for the apparatus in each room. CA2 indicates a controlling switch for the apparatus in the room A2. CA3 indicates a controlling switch for the apparatus in the room A3. CB2 indicates a controlling switch for the apparatus in the room B2. CB3 indicates a controlling switch for the apparatus in the room B3. Each of these switches comprises mechanism for passing current through the loud speaker by connecting it with the output transformer which is diagrammatically indicated at OT.

Associated with each of the busbars on the board B and located at suitable points which may be adjacent the program clock PC are master talking switches which connect the talking circuit to the busbars and thus to the apparatus in all of the rooms connected to the busbars. MT2 indicates a master talking switch associated with busbar 2 and controlling the master talking circuit to the apparatus in rooms A2 and B2 both of which are shown connected with the busbar 2. MT3 indicates a master talking switch associated with the busbar 3 and controlling the master talking circuit with the apparatus in rooms A3 and B3 both of which are shown connected with the busbar 3. If desired these master controlling switches may be so arranged that all or a plurality of them may be thrown together and operate for a plurality of busbars.

Associated with the program clock contacts for the various busbars are switches which may automatically close the signaling circuits for the busbars even when the talking circuit is in operation and when the signaling circuit is otherwise open these switches will close the signaling circuit and operate the signals in all of the rooms connected to the respective busbars as long as the program clock PC makes the busbar contact. S2 indicates a solenoid switch associated with the program clock busbar contact 2 so as to operate the signals in rooms A2 and B2 and any other rooms which are connected with the busbar 2 when the program clock contact 2 is made although the apparatus may otherwise be in position for operating the loud speakers by operation of the switch MT2 or CA2 etc. S3 indicates a solenoid switch associated with the program clock busbar contact 3 so as to operate the signals in rooms A3 and B3 and any other rooms which are connected with the busbar 3 when the program clock contact 3 is made although the apparatus may otherwise be in position for operating the loud speakers by operation of the switch MT3 or CA3 or CB3 etc.

20 indicates a device for bringing into the output transformer OT of a power amplifier or audio amplifier, radio set or phonograph the matter which is to be distributed through various loud speakers. The device 20 may therefore be taken to represent a microphone

for direct speaking etc. or a phonograph for reproduction or a radio or telephone receiving circuit or the like. The waves from the device 20 are received and suitably transformed in the output transformer OT for transmission through the system by mechanism and arrangements well known in the art and therefore not necessary to be described in detail here. The amplifier may be omitted if the source of audio energy is of sufficient power to operate the loud speakers of the system.

In order to clearly indicate the character of the invention the paths and circuits of the apparatus will be described in such a way as to indicate the effects of the manipulation and operation of the various switches.

With the switches in the condition indicated on the drawing it will be seen that when the program clock has closed the contact 2 current will pass through the wire 21 to the lower contact 22 of the master talking switch MT2 to the switch arm 23 of that switch into the busbar 2 and through the plug A2P and through the wire 24 to the lower right hand contact 25 of the controlling switch CA2; through the switch lever 26 the wire 27 to the lower left hand contact 28 and the left hand switch lever 29 through the wire 30 to the signal mechanism 11 in the room A2 and by the wire 31 to the negative side of the battery. At the same time current will pass from the busbar 2 through the plug B2P and the wire 32 to the lower right hand contact 33 of the controlling switch CB2 through the right hand switch arm 34 and the wire 35 to the left hand contact 36 and the left hand switch arm 37 and by way of the wire 38 to the signal mechanism 15 in the room B2 which is connected to the return wire 31. In a similar way the closing of the contact 3 on the program clock PC will cause the signals 13 and 17 in the rooms A3 and B3 to be operated through the switches CA3 and CB3.

When it is desired to operate the loud speakers controlled by busbar 2 such as A2 and B2 the master talking switch MT2 may be operated so as to place the switch arm 23 in contact with the upper contact 39. This causes current from the output transformer OT to pass through the wire 40 to the right hand contact 41 of the switch S2 through the switch arm 42 and by the wire 43 to the contact 39 of the switch MT2 and through the switch arm 23, which is now in contact with 39, through the busbar 2 to the plug A2P and through the wire 24, the contact 25, the arm 26, the wire 27, the contact 28, the arm 29 and the wire 30 to the loud speaker 12 the other side of which is connected through the wires 31 and 44 to the output transformer OT completing the circuit. At the same time current will go from the busbar 2 through the plug B2P and the wire 32 to the contact 33, the arm 34, the wire 35, the contact 36. The arm 37 and the wire 38 to the loud speaker 16 in the room B2 whence connection is made through the wires 31 and 44 to the output transformer OT.

In like manner the switch MT3 may be thrown to connect the talking circuit to the loud speakers 14 and 18 in the rooms A3 and B3 which are connected to the busbar 3.

It will be understood that although the signal mechanism and the loud speaker at the various rooms are connected in parallel, the battery or signal current will not normally operate the loud speakers but the sound produced in them will be very small and more or less negligible nor will

the talking current normally operate the bell or signal mechanism.

It will be noted that in moving the arm 23 of the switch MT2 into engagement with the contact 39 it has been lifted from engagement with the contact 22. The opening at 22 breaks the signaling circuit for the busbar corresponding to the contact 2 as described above. In order to allow for the time signal when demanded by the operation of the program clock PC the solenoid switch S2 has been provided. When the contact 2 is made on the program clock PC current will come from the battery 10 by the wire 21 to the contact 2 and will pass by the wire 45 through the solenoid S2 and by the wires 46 and 44 to the negative side of the battery. This will energize the solenoid of the switch S2 so as to attract the switch arm 42 to the contact 47 thus for the time being breaking the talking circuit at the contact 41. The talking circuit will thus remain open for the short time that the contact 2 is made on the program clock. The closure at the contact 47 in the switch S2 provides a path from the positive side of the battery through the wires 21 and 45 to the contact 47 and the switch lever 42 through the wire 43 to the contact 39 of the switch MT2 and the switch arm 23 to the busbar 2 and thence through the plug A2P and the wire 24 to the contact 25 of the controlling switch CA2; through the switch arm 26, the wire 27, the contact 28, the switch arm 29 and the wire 30 to the signaling mechanism 11 and through the wire 31 to the negative side of the battery. The signaling mechanism 15 in the room B2 will be energized at the same time. The energization of the signaling mechanism will continue as long as the contact 2 is made by the program clock PC and when that contact is broken the signaling circuit will be broken and the talking circuit restored by deenergization of the solenoid of switch S2 allowing the switch arm 42 of the switch S2 to return to the contact 41. Each of the busbars may be provided with similar mechanism. The master talking switch MT3 and the solenoid switch S3 associated with the busbar 3 have been illustrated and it will be observed that they may be operated to close the talking circuit for the instruments connected with the busbar 3 and allow that circuit to be opened and the signaling circuit closed during the short time when the program clock PC closes its contact 3.

Normally the switches may all lie in the positions indicated in the drawing. It may be desired, however, to operate the signals in some or all of the rooms by manual means and this is provided for in the controlling switches exemplified by CA2, CB2, CA3, CB3, it being understood of course that similar individual switches may be provided for the apparatus which is located in each room of the school or other building. In order to energize the signal 11 in the room A2 the switch arm 29 of switch CA2 may be moved from the contact 28 to the contact 48. In this condition current will pass from the positive side of the battery 10 through the wire 21 to the wire 49, to the contact 48 of the switch CA2 through the switch arm 29 and the wire 30 to the signal mechanism 11 which is connected to the negative side of the battery 10 by the wire 31. It will be observed that this operation of the lever arm 29 of the switch CA2 will have no effect upon apparatus in any of the rooms other than the room A2. Since the talking circuit to the room A2 when in operation passes through the contact 28 and the switch arm 29 of the switch CA2 it is

obvious that upward movement of the arm 29 to operate the signal mechanism 11 will break the talking circuit at the contact 28 which may be remade when the arm 29 returns to its normal position on the contact 28.

It will be remembered that the master talking switch MT2 connected the talking circuit to all of the loud speakers connected with the busbar 2. Provision is made in the individual control switches CA2, CB2, CA3 etc. to energize the loud speakers in individual rooms without at the same time energizing all speakers connected with the same busbar. For instance, the switch arm 26 of the control switch CA2 may be brought into contact with the contact 50 at the right of the switch CA2. In this condition a circuit will be closed from the output transformer OT through the wire 48 to the contact 41 of the switch S2, the switch arm 42 the wire 43 and the wire 51 to the contact 50 and through the switch arm 26 and the wire 27 to the contact 28, the switch arm 29 and the wire 30 to the loud speaker 12 the other side of which is connected through the wires 31 and 44 to the output transformer OT. It will be noted that when the switch arm 26 is thus thrown to complete the individual talking circuit it does not interrupt the circuit through the solenoid of switch S2. Thus when the talking circuit through the loud speaker 12 is completed by contact of the switch arm 26 with the upper contact 50 the switch S2 remains free to operate the signal mechanism 11 when the program clock PC closes its contact 2. When this happens the solenoid S2 will be energized as before by current coming from the battery through the wire 21 and the contact 2 on the program clock PC the wire 45 to the coil of the switch S2 and by the wires 46 and 44 to the other side of the battery 10. At this time the circuit for operating the signal 11 will come from the battery 10 through the wire 21 and the contact 2 on the program clock PC through the wire 45 to the contact 47 of the switch S2 through the switch arm 42, the wires 43 and 51 to the contact 50 through the switch arm 26 and the wire 27, the contact 28, the switch arm 29 and the wire 30 to the signal device 11 the other side of which is connected through the wire 31 to the other side of the battery 10.

The details of the mechanism for throwing, operating and holding the various switches of the system forms no part of the present invention and is not described since they are well known in the art. It will be observed that the switches represented by S2 are so made that normally the switch arm 42 engages the contact 41 and is drawn from such position and into contact with 47 only while the coil of the switch is energized returning to contact with 41 when the coil is de-energized. In the series of switches exemplified by CA2 the arm 29 is normally in contact with 28 but may be lifted, preferably manually, therefrom and held in contact with 48 the arrangement being such that when it is released it will return to contact with 28. The switch arm 26 of the switch CA2 while shown in contact with 25, which may be considered its normal position, may be moved into contact with 50 and preferably may be held or locked into that position and so remain as long as it is desired to maintain the talking circuit closed. When the locking or holding mechanism is released the switch arm 26 should return to contact with 25. In the series of switches exemplified by MT2 the switch arm 23 is normally in contact with 22

but may be moved and held or locked into contact with 39 as long as it is desired to keep the talking circuit closed. When the lock or holding mechanism is released the arm 23 should return to contact with 22.

5 A variation of the system may be made where 10 alternating current is used for operating the bell or other signaling mechanism and this may consist of simultaneously applying both signaling 15 and talking voltage or superimposing the signaling voltage upon the talking voltage when signaling is desired. The way such a system may be arranged and operated may be seen from the 20 diagrammatic fragment indicated in Fig. 2 of the drawings. Apparatus associated with two 25 rooms only is indicated but it will be understood that the apparatus may be duplicated and applied to as many rooms as necessary.

In Fig. 2, A represents the apparatus located 30 for instance in the room of a school comprising 35 a bell or other signaling device 60 placed in parallel with loud speaker 61. As a means of additional protection a condenser C may be placed in the branch containing the loud speaker 40 although this is not essential and it may be omitted if a properly designed loud speaker is used or it may be replaced by a current limiting resistor. PC represents the program clock. MT indicates a master talking switch for the current 45 associated with contact 2. At CA is represented a control switch for the apparatus A and at S is represented a solenoid signal switch. OT represents the output transformer and AS represents a source of alternating current for operating 50 the bells or other signaling mechanism. The switches are illustrated in their normal position to connect the bell-ringing or signaling system when the appropriate contact is made in the program clock PC. The path of the current may 55 be traced from the source AS through the wire 62 and the contact 2 on the program clock PC which is connected to the busbar, through the plug AP and the wire 63 to the contact 64 shown at the lower right hand side of the switch CA through the switch arm 65 and the wire 66 to the lower left hand contact 67, the switch arm 68 and the wire 69 to the bell or signaling mechanism 60 the other side of which is connected through the wires 70, 71 and 72 to the source of 60 alternating current AS. It will be understood of course that this circuit will be closed only at the prearranged times for which the program clock is set. It will be understood also as many other local signaling apparatus as desired may be connected through and operated from the busbar 2.

In order to transmit matter to the loud speakers 61 in the rooms controlling the busbar 2 the master talking switch MT may be closed. This will close a path from the output transformer OT through the wires 73 and 74 through the closed switch MT and by the wires 75 and 76 to the busbar 2 and through the plug AP and the wire 63 to the lower contact 64 in the switch CA through the switch arm 65 and the wire 66 to the lower left hand contact 67 and through the switch arm 68 and the wire 69 to the loud speaker 61 the other side of which is connected to the other side of the output transformer OT through the wires 70, 71 and 72. 65 It will be noted that this talking circuit closed by the switch MT does not interrupt the signaling circuit described above. It will be obvious then that with the master talking switch MT closed the program clock PC may operate to close 70 the signaling circuit and both signaling and 75 the signaling circuit.

talking circuits will pass through the wire 69 into the apparatus in the room A and by properly designing the apparatus and properly selecting the character of the currents both loud speaker and signaling mechanism may be operated.

It may be desired from time to time to operate the signaling mechanism 60 independently of the program clock PC and this may be done by manual or other operation of the switch arm 10 68 of the switch CA. By moving the arm 68 away from contact 67 the talking circuit will be broken and when the arm 68 reaches the upper contact 78 it will close a signaling circuit from the source of current AS through the wire 79, 15 the contact 78, the switch arm 68 and the wire 69 to the bell or signaling mechanism 60 the other side of which is connected through the wires 70, 71 and 72 to the other side of the current source AS. The switch arm 68 when released may return to the contact 67.

When it is desired to operate not all the loud speakers associated with busbar 2 but only the loud speaker at A the switch arm 65 of the switch CA may be moved from contact 64 on to 25 contacts 80 and 81 where it may be held or may be locked into position for as long a period as it is desired to operate the loud speaker. The talking circuit in this condition is from the output transformer OT through the wires 73 and 30 82 to the contact 81, the switch arm 65, the wire 66, the contact 67, the switch arm 68 and the wire 69 to the loud speaker the other side of which is connected through the wires 70, 71 and 72 to the other side of the output transform- 35 er OT.

It will be remembered that the signaling circuit controlled by the program clock PC as indicated above passed through the contact 64 and the switch arm 65. When the switch arm 65 is 40 moved from contact 64 this circuit is broken. To provide for the operation of the signaling circuit under the control of the program clock PC when the switch CA has been thrown to close the talking circuit a solenoid switch S is provided. When the program clock PC makes its contact at 2 the signaling circuit from the source of supply AS passes through the wire 62, the busbar 2, the wire 76, the wire 83, the solenoid of the switch S the other side of which is connected to the other side of the source of supply AS through the wires 84, 71 and 72. The energization of the solenoid of the switch S will cause the switch arm 85 to engage the contact 86 thus closing a circuit for signaling current 55 passing from the source of current supply AS through the wire 62, the busbar 2, the wires 76 and 83 to the switch arm 85, through the contact 86 and by the wire 87 to the contact 80 which is in engagement with the switch arm 60 lever 65. The circuit then passes from the switch arm 65 through the wire 66, the contact 67 the switch arm 68, the wire 69 to the signaling mechanism 60 the other side of which is connected to the other side of the source of supply 65 AS through the wires 70, 71 and 72.

It will be observed that when the signaling circuit is closed for operation during the time the talking circuit is closed both circuits pass to the apparatus at the room A part operating the 70 loud speaker and part operating the signal mechanism arranged in parallel. The various components of the circuits and instruments may be so designed, installed and constructed that but a very small amount of the signaling current 75

passes through the loud speaker and a very small amount of power from the output transformer is consumed by the signaling mechanisms. In this arrangement the talking circuit is not interrupted for the operation of the signals.

The system has been described as comprising a signaling mechanism and a loud speaker at the various rooms or local stations controlled and operated from the main central station which, as above indicated, may or may not be the office of the principal. No means has been indicated at the individual rooms for controlling or cutting in or out the mechanism but obviously each portion or all of the apparatus in each room may have associated with it switches for connecting or disconnecting it with the system.

In many schools there is already installed a signaling system controlled manually or by a program clock. The modern trend is to install in schools a central radio and announcing system so that from some central point radio may be switched to any room or group of rooms through loud speakers mounted in the individual rooms and the principal or others may address one or more class rooms or the auditorium. Such programs starting either from the auditorium or other points within or without the school, or phonograph music or the like may be played through the various loud speakers. This has generally necessitated a second complete wiring system to every room adding considerably to the expense in a new building and making sound installations practically prohibitive in old buildings. The present invention comprises an arrangement by which a sound system may be added without appreciable additional wiring either in new installations or where old signaling systems are already installed and at the same time in such a manner as to give the signal preference at all times over the sound system.

It will be understood that satisfactory operation of the system is dependent upon the relation of the bell or other signaling mechanism and the speakers and their circuits which must be such that the voltage and frequencies required to operate the loud speaker at satisfactory volume will not normally operate the signaling mechanism. The voltage or the voltage and frequencies of the signaling circuit must be such that they will not normally operate the loud speaker nor interfere with nor injure the same.

The system may be varied in numerous ways, such as connecting several bells in multiple with one loud speaker, or several speakers in multiple with one bell, or in any combination desired. The master switch may be in one section, or there may be sub-masters for each program circuit. The system could be made to operate effectively by placing the loud speaker in series with the bell leaving everything else practically the same except for the proper adjustment of the operating voltages. There are of course many detailed variations which can be made in these circuits and still produce an operable system.

The invention has been disclosed in specific forms, but is not confined to the details shown as it may be embodied in other arrangements and in other apparatus.

I claim as my invention:

1. In a transmission system a plurality of signaling mechanisms, a plurality of loud speakers each in parallel with a signaling mechanism, means at a remote point for selectively operating the individual signaling mechanisms, means at a remote point for selectively operating the in-

dividual loud speakers, means at a remote point for selectively operating a group of the signaling mechanisms, means at a remote point for selectively operating a group of the loud speakers, a program clock for operating the signals at predetermined intervals, and means controlled by the clock for interrupting the operation of the loud speakers and operating the signaling mechanisms and subsequently restoring the operation of the loud speakers.

2. In a transmission system a plurality of signaling mechanisms, a plurality of loud speakers each in parallel with a signaling mechanism, means at a remote point for selectively operating the individual signaling mechanisms, means at a remote point for selectively operating the individual loud speakers, means at a remote point for selectively operating a group of the signaling mechanisms, means at a remote point for selectively operating a group of the loud speakers, a program clock for operating the signals at predetermined intervals, and means controlled by the clock for operating the signaling mechanisms when loud speaker controlling mechanism is in position for operating the loud speakers.

3. In a transmission system a plurality of signaling mechanisms, a plurality of loud speakers each in parallel with a signaling mechanism, means at a remote point for selectively operating the individual signaling mechanisms, means at a remote point for selectively operating the individual loud speakers, means at a remote point for selectively operating a group of the signaling mechanisms, means at a remote point for selectively operating a group of the loud speakers, a program clock for operating the signals at predetermined intervals, and means controlled by the clock for operating the signaling mechanisms when loud speaker controlling mechanism is operated.

4. In a transmission system a plurality of signaling mechanisms, a plurality of loud speakers each in parallel with a signaling mechanism, means at a remote point for selectively operating the individual signaling mechanisms, means at a remote point for selectively operating the individual loud speakers, means at a remote point for selectively operating a group of the signaling mechanisms, means at a remote point for selectively operating a group of the loud speakers, a program clock for operating the signals at predetermined intervals, and means controlled by the clock for operating the signaling mechanisms when loud speaker controlling mechanism is passing through the system.

5. In a transmission system a plurality of signaling mechanisms, a plurality of loud speakers each in parallel with a signaling mechanism, means at a remote point for selectively operating the signaling mechanisms, means at a remote point for selectively operating the loud speakers, a program clock for operating the signals at predetermined intervals, and means controlled by the clock for interrupting the operation of the loud speakers and operating the signaling mechanisms and subsequently restoring the operation of the loud speakers.

6. In a transmission system a plurality of signaling mechanisms, a plurality of loud speakers each in parallel with a signaling mechanism, means at a remote point for selectively operating the individual signaling mechanisms, means at a remote point for selectively operating the individual loud speakers, a program clock for operating the signals at predetermined intervals, and means controlled by the clock for operating the signaling mechanisms and subsequently restoring the operation of the loud speakers.

- means controlled by the clock for interrupting the operation of the loud speakers and operating the signaling mechanisms and subsequently restoring the operation of the loud speakers.
5. 7. In a transmission system a plurality of signaling mechanisms, a plurality of loud speakers each in parallel with a signaling mechanism, means at a remote point for selectively operating a group of the signaling mechanisms, means at 10 a remote point for selectively operating a group of the loud speakers, a program clock for operating the signals at predetermined intervals, and means controlled by the clock for interrupting the operation of the loud speakers and operating 15 the signaling mechanisms and subsequently restoring the operation of the loud speakers.
8. In a transmission system a plurality of signaling mechanisms, a plurality of loud speakers each in parallel with a signaling mechanism, means at a remote point for selectively operating the signaling mechanisms, means at a remote point for selectively operating the loud speakers, a program clock for operating the signals at predetermined intervals, and means controlled 20 by the clock for operating the signaling mechanisms when loud speaker controlling mechanism is in position for operating loud speakers.
9. In a transmission system a plurality of signaling mechanisms, a plurality of loud speakers each in parallel with a signaling mechanism, means at a remote point for selectively operating the signaling mechanisms, means at a remote point for selectively operating the loud speakers, a program clock for operating the signals at predetermined intervals, and means controlled by the clock for passing signaling current through the system when loud speaker current is passing 10 through the system.
10. In a transmission system a plurality of signaling mechanisms, a plurality of loud speakers each in parallel with a signaling mechanism, means at a remote point for selectively operating the individual signaling mechanisms, means at a remote point for selectively operating the individual loud speakers, means at a remote point for selectively operating a group of the signaling mechanisms, means at a remote point for selectively operating a group of the loud speakers, a program clock for operating the signals at predetermined intervals, and means controlled by the clock for operating the signaling mechanisms with the loud speaker controlling mechanism in 15 any position.

HUGO COHN.
